UNITED STATES PATENT OFFICE.

JOHN HENRY BIRCH AND JAMES SAMUEL FOLEY, OF WEST BROMWICH, ENGLAND.

TYPE-WRITING MACHINE.

No. 876,685

Specification of Letters Patent

Patented Jan. 14, 1908.

Application filed October 19, 1906. Serial No. 339,683.

To all whom it may concern:

Be it known that JOHN HENRY BIRCH and JAMES SAMUEL FOLEY, subjects of the King of Great Britain, residing at High Street, 5 West Bromwich, near Birmingham, England, have invented certain new and useful Improvements in Type-Writing Machines, of which the following is a specification.

This invention has relation to type-writing machines and has for its object to construct 10 arrange and mount the platen-carriage and platen in such a manner as to insure the light, silent and practically frictionless running of the machine, and to facilitate the detachment or removal of either the platen 15 alone or of both the platen and carriage individually or collectively from the body or standing frame for rendering every part of the mechanism fully accessible for cleaning, 20 inspection or repair.

Figure 1 of the accompanying drawings represents a top-side plan, partly in horizontal section, of the rear portion of a typewriting machine constructed in accordance with 25 this invention and showing the arrangement of the detachable carriage upon which the platen (not shown) is mounted. This view also shows the construction of the ball bearing rollers upon which the carriage is mounted, 30 in addition to representing in dotted lines, the arrangement of the connections between the said platen carriage and the spring-actuated mechanism for imparting the intermittent or step-by-step movement to the 35 carriage and platen when either the writing keys or the spacing bar of the machine is operated. Fig. 2 is a view showing, partly in plan and partly in horizontal section the means whereby the traction spring connections may be temporarily anchored to the 40 frame of the machine when the carriage as well as the platen are removed. Fig. 3 is an underside plan of the platen of the supporting frame separably, showing the arrangement of the locking slide whereby the 45 said platen and its carriage are detachably secured to the frame. This view shows the said slide in its operative or fastening position, while Fig. 4 represents the position in 50 which the said slide has to be placed in order to release the carriage. Fig. 5 is an end elevation, partly in section, of the carriage and platen mountings showing the arrangement and disposition of the various supporting and 55 fastening devices. This view shows the carriage thrown back from its normal position

into the rearmost of the two other positions which it may be made to assume by the actuation of platen shift keys for writing capitals or figures. Fig. 6 is a similar view but shows the platen in the normal position which it always assumes until either the "capitals" or "figures" shift key is operated. Fig. 7 shows in end elevation the cylinder and the carriage separated from one another and disconnected and detached from that part of the frame or body of the machine to which they are normally secured. Fig. 8 is a detail view showing the arrangement of a silencing spring which is used in connection with the carriage escapement mechanism for insuring silent working.

The same letters of reference indicate corresponding parts in the several figures of the drawings.

The carriage *a* and platen *b* are arranged at the back of the machine between the type-bar housing and a horizontally-disposed margin-stop rail *c*, and are mounted upon anti-friction ball bearing rollers running upon a system of guide rails as hereinafter described and adapted to render the movements of the carriage smooth, silent and practically frictionless. When applied to a machine of the "Universal" key-board type as shown in the drawings the cylinder (which is arranged above its carriage) is supported by a system of parallel action links operated and controlled by the "capital" and "figure" shift keys whereby the position of the said platen in the horizontal plane may be changed for printing either capital or figures and the like, as the operator may require; it being understood that in the normal position of the platen, which is shown in Fig. 6, the actuation of the keys will cause the small character types to print upon the paper. One pair of the links *d* of the parallel motion system are disposed between the type-bar housing and the platen-carriage and are arranged to support at their upper ends, the top guide-rail *e* to which the platen frame is detachably connected as hereinafter described, so that when either shift-key is operated and the links are made to swing in a direction at right angles to the length of the platen, they carry the top-guide rail and the platen with them, and transfer the latter from the normal position shown in Fig. 6 into either the rearmost position shown in Fig. 5 or into an intermediate position between the two—corresponding to the throw or angular move-

ment which the links d are constrained to make when the "capitals" shift key is operated, but when the said key is released, the shift-key spring d^1 returns the links, the 5 guide rail and the platen to their normal positions and retains them there during the whole of the time that the machine is being operated for printing in small characters. The shift movements of the platen are independent of and do not affect the carriage which is only adapted to traverse to and fro in a plane parallel to the axis of the said cylinder and therefore, the rearmost pair of links f of the parallel motion cylinder mountings are carried by the said carriage, to 10 which their lower ends are suitably pivoted at f^1 while their upper ends are provided with open topped or forked bearings f^2 for the reception of trunnion pins b^1 which are attached to the outer sides of the end plates 15 of the cylinder-frame b^2 at suitable points for preserving the parallelism of the platen on its position being changed when the guide rail links d are operated by one of the shift keys.

The platen is constrained to traverse with the carriage along the top-guide rail e , which, in addition to forming the connection between the shift key mechanism and the 20 cylinder, also serves as one of the supports for the latter, and for this purpose, the front of the platen frame is fitted with a pair of anti-friction rollers g each having a single row of balls arranged between its inner periphery and a fixed pivot pin (as hereinafter described) and adapted to run along the top of the said rail. These rollers are preferably grooved to saddle upon the rail and to admit of them being used as part of the means for 25 detachably connecting the platen to the said rail, while the other element of the connection is formed by a tongue or catch h which is mounted on the platen frame and is adapted, when in its extended and operative position (as shown in Figs. 3, 5 and 6) to engage 30 under the rail and positively prevent the guide roller or rollers from being lifted or disengaged therewith, without however, interfering with the free and frictionless rolling movement when the carriage is in motion. This tongue catch is however so arranged that when it is desired to detach the platen it may be withdrawn from under the rail, and for this purpose, it is carried by a 35 slide h^1 having a system of inclined slots h^2 working over fixed pins or studs h^3 on the platen frame, and the slide itself is connected to a rod h^4 extending beyond the end of the said frame and adapted when moved in one 40 direction by the operator, to traverse the slotted plate over the pins and withdraw the catch clear of the rail (see Fig. 4) while by moving the said rod in the opposite direction the reverse movement is imparted to the said 45 catch for taking the same into the engaging

position beneath the rail in which it co-operates with the platen anti-friction roller or rollers for locking the said platen to the shift mechanism.

The connection between the platen frame 70 b^2 and the back links f of the shift action is rendered detachable by forming the upper ends of the said links with the forked bearings f^2 for the reception of the frame trunnions b^1 and by pivoting small hooked catches f^3 75 to the outsides of the said links, such catches being adapted when in one position to engage over the extending ends of the said trunnions as shown in Figs. 5 and 6, and retain them in their bearings, but when they are turned clear of these trunnions, the platen is free and may (provided the locking tongue which engages under the top guide roll has been previously withdrawn) 80 be lifted out of the link bearings as shown in Fig. 7 and thus completely detached from its carriage.

The carriage is connected to the traction or main-spring of the machine, and in addition to supporting the platen, it also has 85 mounted upon it the usual escapement dogs i which co-operate with a ratchet-toothed escapement rack i^1 for controlling the carriage traverse under the pull of the said traction spring, the escapement release key, carriage bell and stop mechanism and other accessory parts. The said carriage is mounted in a space between the escapement rack-bar i^1 and the margin adjustment rail c , 90 which is carried by small pillars or standards along the extreme back edge of the standing frame, and for the purpose of guiding the said carriage in its rectilinear movement and rendering the action noiseless and smooth the rearward side of the same is fitted 95 with a system of anti-friction ball-bearing rollers two or more of which j^1 are grooved and adapted to run along a fixed guide rail j^2 attached to the standing frame and set 100 parallel with the top-rail of the platen shift link mechanism while another roller j^3 is mounted in a rearward extension of the carriage so as to come under and run along the underside of the elevated margin-adjustment rail c which thus prevents the other 105 rollers of the carriage from rising or jumping the guide rail when the machine is being operated at a high speed. To co-operate with this system of anti-friction rollers, the carriage is also provided with a pallet or 110 bracket plate k on the top of which the toothed dogs i of the escapement mechanism are mounted; and this pallet is extended beyond the forward edge of the carriage into a tongue k^1 which is adapted to engage with 115 in a longitudinal groove or race-way k^2 formed along the back edge of a stationary guide-bar k^3 which is fixed to the frame below the escapement rack-bar and parallel 120 with the top and bottom rails. This ar- 125

angement preserves the parallelism of the carriage, but the alinement or adjustment of the platen with the system of guide rods may be facilitated by carrying the anti-friction rollers in brackets which are capable of independent adjustment in directions at right angles to the axis of the platen, while in order to prevent the pallet-tongue from rattling or chattering in the guide race, the 10 pallet itself is hinged to the carriage or mounted on a rock shaft having its bearings in the said carriage and a light spring such as k^4 is arranged to act upon its underside and by tending to force the same upwards to keep the said tongue in just sufficient frictional contact with the top of the guide race in the fixed bar to prevent play and chatter and thus render the motion silent.

20 In addition to the margin-adjustment rail coöoperating with the roller of the carriage extension for keeping the principal rollers down upon the main guide rail, the said margin rail also serves as the means for retaining 25 the carriage in its proper position at the back of the machine, and in order to provide for the complete detachment and removal of the said carriages together with the platen, the margin rail is made so that it may, when desired, be disconnected and swung quite clear 30 so as to leave the way open for the carriage to be withdrawn from the back of the machine. This may be effected by pivoting one end of the rail to one of its supports c^1 so that it may 35 swing in a horizontal plane as shown in dotted lines in Fig. 1, and by providing a simple locking device for securely fastening the opposite end to the other support c^2 such for instance, as by forming a gap c^3 in the edge of 40 the rail end to engage a neck or reduced part of the pillar or standard c^2 and by fitting a small screw-controlled locking pin or eccentric slide to move across and close the entrance to the said gap after it has passed over 45 the neck of the pillar. With such an arrangement when the margin-rail is swung aside, and the platen fastening slide has been disengaged from the top guide-rail so as to release the said platen from the shift mechanism, and after the carriage has been disconnected from the traction spring, both the carriage and platen can be collectively lifted away from the back of the machine, and then 50 they can be detached from one another if desired, by disengaging the hook catches of the rearward platen-shift links f , from the trunnion studs of the platen frame.

To facilitate the unshipping of the carriage from the main spring the latter is detachably 55 connected to the said carriage through the medium of a cord or light chain m which is adapted to be wound around a drum m^1 by the action of the said spring and to draw the carriage in one direction and to be paid off 60 the said drum and tension the spring when

the said carriage is pushed in the other direction by hand. The connection cord preferably terminates in a small eye-plate m^2 which normally engages over a stud or peg m^3 arranged at the right hand end of the carriage 70 but is capable of being withdrawn therefrom so as to uncouple the said carriage from the spring gear and it may be temporarily anchored to the frame during such time that the carriage is disconnected by providing said 75 frame with a similar peg or stud m^4 over which the eye-plate is passed, as shown in Fig. 2.

As already stated, the ball bearing rollers which support the platen and run upon the top guide rail and also the carriage rollers which run upon the bottom rail and also under the margin rail are each provided with a single row of balls n , interposed between the pivot pin n^1 and the inner periphery of 80 the roller, and in order to facilitate assembly and adjustment of these, it is proposed to form the internal periphery of each roller with a groove or ball race n^2 while each pivot pin carries both a fixed cone n^3 and a screwed-on adjusting cone n^4 whose conoidal surfaces 85 together comprise another V-sectioned race opposed to the race n^2 of the roller and between these inclined surfaces the balls are arranged to run in four-point contact. The 90 central opening n^5 in the roller has obviously to be of less diameter than the V-shaped race, but the annular space included between this opening and the pivot pin is sufficient to admit of the balls being introduced before the 95 adjusting cone is applied, and then this last-named cone, in being screwed home along the said pivot acts upon the ring of inserted balls and expands them outwardly into their proper position within the race n^2 and after 100 the cone has been finally adjusted to admit of the roller running freely upon the ball with lateral play or shake, the same is secured in its adjusted position by means of a lock nut such as n^6 .

Having fully described our invention, what we desire to claim and secure by Letters Patent is:—

1. In a typewriting machine, the combination with a supporting frame, a carriage 115 mounted to operate thereon, and a platen frame shiftable transversely on the carriage and having one side detachably connected to the latter, of a shifting rail mounted on the supporting frame and detachably connected to the platen frame, the shifting rail being movable laterally of its length only for shifting the platen transversely of the carriage and a catch for locking the platen frame to the shifting rail and for permitting 120 its detachment from the latter.

2. In a typewriting machine, the combination with a supporting frame, a pair of platen-supporting links thereon, a guide rail carried by the supporting links, a traversing 125

platen frame connected to the rail, a traversing platen carriage, a second pair of links fulcrumed to and swinging from the platen carriage and supporting the platen frame, a system of grooved rollers mounted upon the platen frame and adapted to traverse the said rail, and a catch carried by the platen frame and guided to move into and out of coöperation with the under side 10 of the said rail for detachably locking the platen frame in operative position.

3. In a typewriting machine, the combination with a supporting frame, of a traversing carriage guided thereon, a pair of vertically-arranged links pivotally supported on the carriage, a platen frame having one of its longitudinal sides pivotally connected to the upper ends of the said links, a second pair of links mounted on the supporting 20 frame and coöperating at their upper ends with the opposite side of the platen frame for guiding the latter for movement in substantially a horizontal plane.

4. In a typewriting machine, the combination with a supporting frame, of a traversing carriage guided thereon, a pair of links pivotally mounted on the carriage, a platen frame detachably engaging the said links a second pair of links mounted on the supporting frame, and having a guide rail connecting them, supporting rollers on the platen frame coöperating with the upper side of the said rail, and a catch movable into and out of coöperative relation with the under 35 side of the rail for detachably locking the platen frame thereon.

5. In a typewriting machine, the combination with a supporting frame, of a traversing carriage mounted to operate thereon, a pair of links pivotally mounted on the carriage and provided with open bearings at their upper ends, a platen frame having projections adapted to detachably engage the open bearings of the said links, catches 45 on the links for locking the said projections in coöperative relation therewith, shifting links pivotally mounted on the supporting frame, and a catch for detachably connecting the shifting links to the platen frame.

50 6. A type-writer machine having the frame thereof provided with a groove in its top, a traversing carriage, and escapement mechanism carried thereby embodying a plate having a tongue arranged to operate 55 longitudinally of the groove, and a silencing spring upon the carriage and which is adapt-

ed to act upon the escapement pallet and retain its edge in contact with the top of the groove in the frame.

7. In a typewriting machine, the combination with a supporting frame, a relatively fixed guide rail thereon, and a movable rail arranged above and adjustable relatively toward and from the fixed rail, a groove being formed in the supporting frame at the 60 opposite side of the fixed rail and opening toward the latter, of a carriage adapted to carry the platen, a part on the carriage co-operating with the under side of the adjustable rail and arranged to disengage therefrom by a relatively lateral movement of the rail, a projection on the carriage coöperating with the groove in the supporting frame, and grooved rollers on the carriage coöperating with the fixed rail to support 65 the carriage and to retain the projection thereon in engagement with its coöperating groove.

8. In a typewriting machine, the combination with a supporting frame having a 70 longitudinal groove thereon, and a relatively fixed guide rail extending parallel to the groove, of a platen supporting carriage having grooved rollers coöperating with the upper side of the fixed rail, a tongue on the 75 carriage held in engagement with the groove on the supporting frame by means of the grooved rollers, and an adjustable rail movable in a direction transverse to the fixed rail and coöperating with a part of the carriage to retain the grooved rollers thereon 80 in coöperative relation with the fixed rail.

9. In a typewriting machine, the combination with a supporting frame provided with a longitudinal groove, and a guide rail, 90 of a platen supporting carriage having rollers arranged to coöperate with the guide rail, a plate on the carriage movable transversely of the plane of movement thereof and having a tongue operating in the groove 95 on the supporting frame, a silencing device interposed between the carriage and the movable plate thereon for absorbing the shock between the said parts.

In testimony whereof we have hereunto 100 set our hand in presence of two subscribing witnesses.
